UNITED STATES PATENT OFFICE.

CLARENCE E. CARAWAY, OF PORT WILLIAMS, OHIO.

GRAIN DOOR FOR FREIGHT CARS.

Application filed March 20, 1924. Serial No. 700,518.

My invention relates to doors for freight cars and more particularly to an auxiliary door or grain door for use in shipment of bulk grain.

In the freight shipments of grain in bulk, such as wheat, barley, oats, shelled corn, and so forth, it is necessary to provide an auxiliary closure inside the usual freight car door, to prevent leakage of the grain in transit and to facilitate the loading and unloading of the car of grain by restraining the more or less fluid body of the grain when the main car door is opened. It is a common practice for grain shippers to nail a succession of boards across the inside of the door opening of the car. This barricade of boards must be broken down when the car reaches its destination. Each shipment requires the erection of a new barricade. Not only does this involve a loss of time and labor, in preparing the car for each grain shipment, but it also involves a considerable loss of material, as the barricade boards are lost or destroyed, when the car is unloaded. In the present invention there is contemplated an auxiliary door or barricade of sectional character, which may form a part of the regular equipment of the car, and capable of being shifted into and out of position as required. The sections of the auxiliary door or grain barricade are relatively adjustable to afford at will a variable discharge opening at the bottom of the door for the release of the cargo of grain, and to provide a second adjustable section at the upper part of the auxiliary door or barricade for inspection purposes and to facilitate the loading of the cars. These sections being adjustable in relation with each other and with the intermediate normally stationary section of the barricade door, enable the device to be folded to compact form when not in use. The collapsible barricade or grain door is mounted upon a traveling carrier or trolley by which when not needed for grain shipment purposes it may be shifted away from the door openings to an out of the way position where it will be suspended close to the wall of the car, readily accessible when needed, but not obstructing the use of the car for other purposes.

The object of the invention is to simplify the structure as well as the means and mode of operation of auxiliary car doors and barricades, whereby they will not only be cheap-

ened in construction, but will be more efficient in use, positive and secure in operation, capable of being easily and quickly adjusted, and unlikely to get out of repair.

A further object of the invention is to provide a grain door or barricade, which may be gradually opened from the bottom, with minimum effort, to permit the escape of the grain from the car in regulated quantity.

A further object of the invention is to provide a normally closed barricade, which will permit easy and ready access to the interior of the car for inspection purposes.

A further and important object of the invention is to provide means for removably mounting these adjustable sections in registry with the car door openings, and to provide a suitable support upon which the barricade may be shifted out of registry with the door when not in use and maintained in readiness for subsequent use.

With the above primary and other incidental objects in view as will more fully appear in the specification, the invention consists of the features of construction, the parts and combinations thereof, and the mode of operation or their equivalents as herein described and set forth in the claims.

Referring to the accompanying drawings, wherein is shown the preferred, but obviously, not necessarily the only form of embodiment of the invention, Fig. 1 is a perspective view of a portion of the interior of a box car, showing the grain door or barricade forming the subject matter hereof, in its adjusted operative position. Fig. 2 is an exterior view of the freight car door with the main door open and the auxiliary or grain door closing the car opening. Fig. 3 is a detail sectional perspective view illustrating the relation of the relatively adjustable section of the door. Fig. 4 is a detail plan view.

Like parts are indicated by similar characters of reference throughout the several views.

Referring to the drawings, 1 indicates a box car of the usual slide door type, of which 2 is the main door or closure, slidably mounted upon the exterior of the car. Obviously, such a car door ordinarily constructed and mounted is not leak tight. Moreover, the grain could not be restrained in the car until the loading operation is completed with the door open and the car

could not be loaded at all with the door closed, if this usual sliding door alone was depended upon. It is for this reason that grain shippers have made a practice of barricading the door to a point above the load line, by nailing boards across it. As a more convenient substitute for such board barricade, there is provided a grain door to be detachably secured to the inside of the car door opening. This grain door consists of a normally stationary secured main or intermediate door section 3, extending in opposite directions beyond the jambs of the car door opening and detachably secured to the side of the car by suitable angle brackets, hasps, bolts, or other forms of attachment. The intermediate and normally stationary main section 3 of the grain door is provided at its opposite ends with guides or ways 4, in which is slidably mounted the bottom section 5 of the door. This bottom section 5 overlaps the lower margin of the intermediate stationary main section 3, and normally rests upon the floor of the car at the bottom of the car door opening. This lower section is vertically adjustable in the guides or ways 4, and may be gradually elevated from the exterior of the car to permit the regulated escape of the grain. To this end, this lower sliding section 5 is preferably though not necessarily provided upon its exterior face with one or more small pry lugs 6, under which a lever or bar may be inserted to elevate the sliding sections. This sliding section is provided with a spring detent 7, engaging in a socket or recess in the outer face of the stationary main intermediate sections 3, when the lower sliding section is in its closed or lowermost position. This spring detent 7 yields outwardly to enable the elevation of the sliding door section 5, and at the upper limit of the adjustment the spring detent will engage over the top margin of the stationary intermediate section 3, or in a second socket opening if desired, to retain the sliding section in its elevated position.

Hinged to the top margin of the stationary intermediate section 3 is an inwardly swinging inspection board 8. The joint between the inspection board 8 and the stationary supporting section 3 is preferably rabbeted and the board 8 is attached by hinges 9 permitting it to be swung inwardly and downwardly. This board 8 in the erected position of the grain door is located above the level of the load line. When swung downward and inward it affords an ample opening between the top of the stationary section 3 and the top of the door opening to permit the entrance of a man over the barricade for inspection of the cargo of grain. At other times this hinged leaf or inspection board is maintained in its upright or enclosed position, in the plane

of the stationary closure section 3 of which it forms an extension, by means of suitable locks or latches accessible from the outside of the car. In the present instance, small lock plates 10 are shown pivoted to the swinging inspection leaf or board 8, and having holes therein through which removable pins may be inserted into registering openings in the upper margins of the guide ways 4. By removing such pins, the leaf may be swung inward and access be had to the car. It will be understood that the grain door or barricade overlaps the lateral margins of the door opening, sufficient distance in both directions to prevent leakage of grain. Moreover, the ends of the sliding lower sections 5 of the door are preferably rabbeted for reception in the grooved guides or ways 4, so that the face of such adjustable panel or section 5 will extend flush with the face of the guide ways 4 and so contact uniformly with the interior face of the car door frame.

When not in use for grain shipment purposes, the auxiliary door or barricade is contracted into compact form by sliding the lower section or panel 5 upward into registry with the main supporting section 3, and then suspending the collapsed or contracted door structure against the inside wall of the car in a position at one side of the car door opening. To facilitate the movement of the barricade door into and out of position and to adjustably attach it to the car, that it may not be discarded or lost, the door is preferably suspended from a trolley carrier. This carrier consists of the frame or hanger structure 11 provided with carrying wheels 12, which engage and travel upon a trolley track 13, secured to the interior wall of the car above the car door opening and extending thence laterally toward the end of the car. While the grain door or barricade structure may be fixedly or rigidly secured to such traveling hanger or carrier device, it is preferably suspended from such hanger by means of cables 14, the lower ends of which are secured to the normally stationary or supporting sections 3 of the door structure, and the upper ends 115 of which are secured to and retrieved by the rotation of a windlass rod 15, mounted in the hanger structure. This windlass rod 15 is provided with a medial crank or offset portion 16, by which the rod may be rotated to wind or retrieve the suspension cables and so elevate the grain door when detached from the car door opening, to an elevated position where it will not interfere with the loading of the car with other merchandise. The collapsed door having been elevated by the rotation of the windlass rod, such windlass rod may be locked by inserting a pin 17 through registering holes in the rod and in a suitable projecting por-

tion of the hanger frame. Thereupon the door may be shifted upon the supporting rack away from the car door opening and held suspended near the top of the car, but 5 easily accessible for the next grain shipment.

Inasmuch as freight cars may be loaded to different heights with different varieties of grain, that is to say, the load line for corn is somewhat higher than that for wheat, and 10 the load line for oats is higher than either corn or wheat, the suspension cables and windlass rod 15 are of material assistance in locating the intermediate door section 3 at various heights according to the character 15 of the grain to be loaded. That is to say, if the cargo is wheat, the intermediate section 3 is set at somewhat greater elevation thereby reducing the interior pressure on the lower sliding section 5 of the door. The suspension cables and traveling carriage therefore, not only facilitate the movement of the collapsible barricade into and out of registry 20 with the door opening, but is of material assistance in temporarily supporting the barricade parts while being secured to the interior 25 of the door opening frame. To further enable the lower sliding section 5 of the barricade to resist the interior pressure of the grain, the section 5 is preferably though 30 not necessarily provided with a dependent bolt or stud 18, projecting below the lower margin of the sliding door section and engageable in a corresponding socket in the bottom of the door frame or sill of the car. 35 As a means of sealing the barricade to prevent the leakage of grain in transit, the lower margin of the sliding section 5 is preferably, though not necessarily provided with a flexible sealing strip 19 of cloth, rubber or other 40 suitable material. This sealing strip 19 is attached to the sliding section 5 in a rabbet formed in the inner face of the door section, in order that when the parts are in collapsed condition, said strips may readily pass beyond 45 the lower edge of the intermediate section 3. When in use such sealing strip extends laterally upon the floor of the car as shown in Fig. 1. Turnbuckles 20 having at their ends, hooks engageable in screw eyes 50 projecting from the outer face of the sliding barricade section side, and located in the frame of the car door opening, may be employed to further secure such sliding door section and to draw it into close relation- 55 ship with the car door frame. To prevent the complete separation of the door or barricade sections 3 and 5, and the loss or misplacement of the loose section, the range of their sliding adjustment is preferably limited 60 by providing a vertically disposed spline or groove 21, in the outer face of the stationary section 3, in which engages a stud 22, mounted in the slideable section 5. The engagement of the stud 22 with the opposite 65 ends of the spline or groove 21, limits the

relative sliding adjustment of the section 5 in either direction.

From the above description there is provided a device of the character described 70 possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, 80 it is to be understood that the invention is not limited to the specific details shown, but that the means and construction herein disclosed comprises the preferred form of several modes of putting the invention into effect and the invention is, therefore, claimed 85 in any of its forms or modifications within the legitimate and valid scope of the appended claims.

Having thus described my invention, I 90 claim:

1. In a barricade for car doors, a unitary structure comprising an intermediate section to be detachably secured to the interior faces of the jambs of a car door, guide ways 95 provided at each end on the intermediate section, a bottom section slidably mounted in said terminal guide ways of the intermediate section, an auxiliary section hinged to the top of the intermediate section and swingable inwardly, a supporting trolley 100 for said sectional barricade, a runway for the trolley upon which the trolley travels to shift the supported barricade sections into and out of registry with the car door opening, and hoisting means connecting the 105 barricade sections with the trolley.
2. In a barricade for car doors, a main section to be detachably secured to the interior faces of the jambs of a car door opening, guide ways provided at opposite ends 110 on the main section, a lower section slidably mounted in such guide ways for vertical sliding movement, a vertically disposed groove in the face of the main section, a stud in the adjacent face of the sliding section engaging in said groove to limit the relative sliding movement of the sections, and a spring detent upon the sliding section 115 for engaging it in adjusted relation with the main section.
3. In a barricade for car doors a unitary structure, a plurality of relatively adjustable sections to be detachably secured across the interior of a car door opening, a trolley, 120 a runway secured to the interior of the car upon which the trolley travels to and fro, a revoluble crank shaft mounted upon the trolley and accessible from the exterior of the barricade, and hoisting cables connecting the barricade sections with the crank 125 130

shaft by which the sections are raised and lowered, said sections being movable into and out of registry with the car door opening by the to and fro movement of the trolley.

4. In a barricade for car doors, a main section of greater length than the width of the car door opening, brackets for securing such section fixedly to the interior faces of the door jambs at mid height position, a lower sliding section also of greater width than the car door opening, guide channels carried by the main fixed section in which the extremities of the lower section engage

for vertical sliding movement, a top section 15 hinged to the main section for inward swinging movement, standards carried by the main section with which the swinging section is engageable when in closed position, means for locking the 20 swinging section to said standards, and means for locking the sliding section relative to the main section.

In testimony whereof, I have hereunto set my hand this 13 day of March A. D. 25 1924.

CLARENCE E. CARAWAY.
